UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF CANADA.

SALES-BOOK.

1,042,637.

Specification of Letters Patent. Patented Oct. 29, 1912.

Application filed November 22, 1911. Serial No. 661,707.

To all whom it may concern:

Be it known that I, EDWARD KIRBY BOTTLE, a citizen of the United States, residing at Elmira, in the county of Chemung 5 and State of New York, have invented certain new and useful Improvements in Sales-Books, of which the following is a full, clear, and exact description, such as will enable others skilled in the art to which it appertains to make and use the same.

This invention relates to sales books, and with regard to certain more specific features thereof, to manifolding sales books particularly adapted for café or restaurant use.

One of the objects of this invention is to provide an improved sales book of the above character permitting simultaneous use of a plurality of live checks.

Another object is to provide a simple and practical book of the above character permitting of ready manipulation.

Another object is to provide an improved form of continuously folded pad.

A further object is to provide a self-contained device of the above character which will be durable in construction and inexpensive to manufacture.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments of this invention, Figure 1 is a perspective view of the book in operative position; Fig. 2 is a central transverse sectional view of the book; and Fig. 3 is a central longitudinal sectional view of the book taken in closed position.

Similar reference characters refer to similar parts throughout the different views of the drawings.

Referring now to the accompanying drawing, particularly Fig. 1, there is shown at 1 a pad holder forming a rear cover upon which is removably mounted a pad 2. This pad 2 comprises a continuously folded web forming a plurality of original and duplicate leaves 3 and 4, respectively, each original 55 leaf being carbonized on the back, as de-

noted by the heavy line 5, throughout the greater portion of its area. The pad is mounted or secured at one end to a loose back 6 adapted to be inserted in a pocket 7 in the cover 1 as shown in Fig. 3. This back, 60 which is preferably made of heavy paper, extends upwardly over one end of the pad and thence inwardly to lie beneath the upper set of leaves as indicated at 8, thereby providing a firm back when recording the transaction and also preventing the transaction 65 from being reproduced upon the lower sets of leaves.

Directly connected with the side and end edges of the pad are a plurality of relatively 70 narrow strips 9 pasted to the edges of the sets of leaves for holding the leaves in normally connected and superimposed relation and preventing the pad from streaming or becoming unfolded when in use. As this 75 strip contacts with only a small portion of the actual edge of each leaf, it will be seen that the leaf may be easily and quickly seized and detached.

A plurality of flaps 10 and 11 are flexibly 80 connected with the cover 1, the latter flap acting as an upper cover for the book when in closed position as shown in Fig. 3. The flap 10 is provided on both sides, at its upper and lower edges, with pockets 12. Similar 85 pockets are also applied to the inside of the cover or flap 11. Each set of pockets is adapted to receive and hold a set of leaves when detached from the pad. As each set of leaves is provided with manifolding 90 means, further entries upon these slips may be made from time to time as desired.

The book may be conveniently used in substantially the following manner: A waiter in a café, for example, after inserting 95 his own number and the table number in the places provided as indicated in Fig. 1, receives an order for the first course from the guest he is serving and enters the same at the top of the original leaf upon the pad. 100 If he is subsequently required to wait upon a second guest, he removes the top set of leaves by pulling the original upwardly and thence forwardly, and detaches the complete set from the pad along perforated lines 13 at 105 the end of each leaf. He then inserts this set of leaves in the pockets provided on one side of one of the flaps. He is then ready, after replacing the protector 8, beneath the top set of leaves, to receive orders from 110

the second guest, as well as to make further entries on the first set of leaves detached. If he is required to wait on more than two guests at the same time he detaches the second set of leaves and inserts them in the pockets upon another flap. In this manner it is seen that with the embodiment herein shown he can wait upon four parties, at the same time keeping four live or active checks simultaneously in use. When the guest calls for his check, the proper set is removed from the pocket or pad as necessary, the original and duplicate leaves are separated and the guest presented with one, while the other is retained by the waiter or disposed of according to the rules of the café. It is thus seen that this invention provides a simple and practical waiter's check book adapted to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

30 Having described my invention, what I claim as new and desire to secure by Letters Patent is:

1. In a manifolding sales book, in combination, a pad having a continuously folded web, and means directly connected with a side edge thereof adapted to prevent the pad from becoming unfolded yet permit the leaves to be detached without mutilation.

2. In a manifolding sales book, in combination, a holder adapted to retain a pad of detachable leaves, a double face flap connected with said holder, and retaining means on both sides of said flap and directly connected therewith adapted to receive and hold the edges of the leaves when detached, whereby further entries may be made upon the detached leaves when desired.

3. In a manifolding sales book, in combination, a pad having a continuously folded web, and means binding the edges of the leaves of said pad to each other at a plurality of places adapted to prevent said pad from becoming unfolded yet permit the leaves to be detached without mutilation.

4. In a manifolding sales book, in combination, a pad having a plurality of sets of original and duplicate leaves, manifolding means connected with each set, and a relatively narrow strip pasted to the edges of said leaves for holding the same in normally adjacent position.

5. In a manifolding sales book, in combination, a pad having a continuously folded web forming a plurality of sets of original

and duplicate leaves, the back of each original leaf being carbonized, means directly connected with said pad adapted to be inserted between the adjacent sets to prevent the transaction being recorded on a lower set, and means directly connected with the side edges of said pad adapted to prevent the pad from becoming unfolded.

6. In a manifolding sales book, in combination, a pad having a continuously folded web forming a plurality of sets of original and duplicate leaves, a back for said pad, a continuation of said back adapted to be inserted beneath the upper set of leaves to prevent duplicating on a lower set, and members directly connected with the leaves along one edge of said pad.

7. In a manifolding sales book, in combination, a pad having a continuously folded web forming a plurality of sets of original and duplicate leaves, a back for said pad, a continuation of said back adapted to be inserted beneath the upper set of leaves to prevent duplicating on a lower set, a manifolding means associated with said pad, and means directly connected with the leaves along one edge of said pad to prevent the pad from becoming unfolded.

8. In a manifolding sales book, in combination, a pad having a continuously folded web forming a plurality of sets of original and duplicate leaves, a back for said pad, a continuation of said back adapted to be inserted beneath the upper set of leaves to prevent duplicating on a lower set, the back of each original leaf being carbonized, and means directly connected with the leaves along one edge of said pad to prevent the pad from becoming unfolded.

9. In a manifolding sales book, in combination, a pad holder, a pad comprising a plurality of sets of original and duplicate leaves mounted thereon, the back of each original leaf being carbonized, a plurality of flaps connected with said pad holder, and pockets in said flaps adapted to receive sets of leaves when detached from said pad, the carbonized backs permitting further entries after the sets of leaves have been detached.

10. In a manifolding sales book, in combination, a pad holder, a double face flap connected therewith, and pockets on both sides of said flap and directly connected therewith adapted to receive the edges of detached sets of leaves, whereby further entries may be made upon the detached sets of leaves as desired.

11. In a manifolding sales book, in combination, a pad holder, a continuously folded web mounted thereon, means securing the edges of said pad together to prevent streaming, a plurality of flaps flexibly connected with said pad holder, and pockets in the upper and lower edges of said flaps adapted to receive detached sets of leaves from said

pad, each set of leaves having manifolding means associated therewith whereby further entries may be made on each set after being detached from the pad.

5 12. In a manifolding sales book, in combination, a pad holder, a continuously folded web comprising a plurality of sets of original and duplicate leaves removably mounted on said holder, means adapted to be interposed beneath the top set of leaves to prevent duplicating on the lower sets, manifolding means associated with each set of leaves, a plurality of flaps connected with said pad holder, and pockets in said flaps

10 for receiving detached sets of leaves from said pad whereby further entries may be made thereon, one of said flaps adapted to act as a cover for said book.

13. In a manifolding sales book, in combination, a continuous pad, and a member engaging and adhering to the outer surface of the edge of the pad. 20

14. In a manifolding sales book, in combination, a continuous pad, and a member engaging and adhering to the outer surface of the side edge of the pad. 25

15. In a manifolding sales book, in combination, a continuous pad, and a member engaging and adhering to the outer surface of a plurality of the edges of the pad. 30

In testimony whereof I affix my signature, in the presence of two witnesses:

EDWARD KIRBY BOTTLE.

Witnesses:
